UNITED STATES PATENT OFFICE

HERMANN LAUCHENAUER, OF ZURICH, SWITZERLAND, ASSIGNOR TO THE FIRM
MASCHINENFABRIK A. D. SIEHL A. G. VORM. A. SCHMID, OF ZURICH, SWITZERLAND

CENTRIFUGAL PUMP INSTALLATION COMPRISING AN AIR-SEPARATING DEVICE

Application filed January 6, 1931, Serial No. 508,942, and in Switzerland January 14, 1930.

This invention relates to centrifugal pump installations, comprising an air-separating device, wherein for the purpose of effecting a suction action in the pump on starting the same, the pressure conduit of the pump is connected with the suction port of the pump by way of an ejector acting in the direction of the suction action of the pump and the suction chamber of said ejector is connected with the suction conduit of the pump by means of a pipe knee extending above the pump.

In a known arrangement comprising special pumps of this type, the entire air-separating device was enclosed together with the pump in a common casing; but this arrangement had the disadvantage that the injector was permanently kept running during the operation of the pump, thus continuously causing eddies in the water circulation inside the pump, which was accompanied by a corresponding loss of energy.

To overcome this drawback it has already been proposed to employ mechanically operated closing members, in the form of shut-off valves, for the circulating conduit of the ejector; but from this arrangement, particularly when low water heads or the pumping of waste water and excrement were involved, so many sources of failure ensued that clogging of the respective closing member was bound to occur, thereby frustrating its effectiveness.

The same applies to similar arrangements in which a non-return valve was provided in the suction conduit.

According to the invention this drawback is eliminated in the pump installation by connecting the air-separator included in the pressure conduit in a known manner with the delivery pressure conduit, by means of a second ejector acting in the direction of the pump delivery and communicating with the first ejector by way of its suction chamber.

Owing to this arrangement, during the operation of the pump, the water is prevented

from circulating in the ring conduit constituted by the pump, the connecting pipe thereof to the air-separator, the ejector and the connecting pipe thereof to the suction side of the pump; so that in the normal operation of the pump no loss of energy is involved.

The device is particularly adapted to be used in connection with installations for pumping waste water and excrement, and for all cases where every time when the pump is started replenishing of the suction conduit is to be avoided.

In the accompanying drawings, two constructional forms of the installation are illustrated, wherein

Fig. 1 is a schematical elevation of a first constructional form; and

Fig. 2 a similar view of a second constructional form;

Fig. 3 shows a detail section of Fig. 2.

In the constructional form, as shown in Fig. 1, the centrifugal pump 1 has a pressure connection 1d which is connected with the air separator 3, situated above the pump, by a horizontal connecting pipe 2. The lower end 70 of the air-separator communicates with a nozzle 3a of an ejector II, the delivery end 5 of which is connected with the pressure conduit 6 containing a non-return valve 7. To a lateral connection 8 of the suction chamber 4 of the ejector II, the nozzle 9 of another ejector I is fastened, the delivery end 10 of which communicates with the suction end 1s of the pump 1. The suction pipe 12 is formed at its upper end with a knee 13 extending above 80 the connecting pipe 2 and communicating with an upwardly projecting pipe connection 11 of the ejector II. At the very top, the knee 13 is provided with an air inlet valve 13a. The pressure conduit 6 includes a vent or 85 snuffle valve 14.

The operation of the described auxiliary device is as follows:

Owing to the elevated knee 13 of the suction conduit, the water is permanently prevented

from completely flowing off through the suction conduit even when the pump is stopped; so that the entire device with the inclusion of the pump is at all times filled with water at least up to the level n . As soon as the pump starts to run, the ejector I is rendered operative, so as to cause the water contained in the ring conduit, constituted by the pump 1, connecting pipe 2, air-separator 3, pressure conduit and ejector II, ejector I and delivery end 10, to circulate and to remove the air from the suction conduit by action of the ejector I, thus initiating the suction action of the pump immediately. As soon as the pump begins to deliver, the ejector II is also rendered operative in the direction of the delivery, and the relative capacities of the ejectors I and II are such that the ejector II discharges the entire output of the pump into the delivery pressure conduit, thus rendering the ejector I inactive, so much more, as the pipe connection 8 is branched off laterally of the suction chamber 4; i. e., at right angles to the spout issuing from the ejector II. Consequently, the water circulation in the above-described ring conduit is ceased, so that no loss of energy is involved.

Alternatively, the air-separator 3 may be omitted and in its place an air pressure-equalizing device, in the form of a vent valve, inserted in the pressure conduit, or else the air-separator may directly be provided with a vent valve.

An arrangement of this kind is shown in the Figures 2 and 3. The vent valve V illustrated in Fig. 3 is mounted within a housing 21 and provided with a valve casing 22 accommodating a valve body 23 which opens downwardly. Above the valve seat in the valve casing 22, lateral air inlet openings 22a are bored. The stem carrying the valve body is passed through the top of the valve casing and guided at its upper end by means of a transverse pin in longitudinal slots of two intercrossing links 25, the outer ends of which are pivotally mounted in the housing 21. The other ends of the two links are engaged by connecting rods 26 of two armatures 27 of electromagnets. The coils 28 of the magnets are connected in series via the loop conductor 29 with the supply conduit of the driving motor.

Fig. 2 shows the manner in which the valve is assembled with the automatically sucking centrifugal pump installation comprising a driving motor M for the centrifugal pump P, an air-separator N directly connected to an upper flange of the pump and communicating with the pressure conduit T of the pump P by means of a connecting pipe R, whereby the suction action of the centrifugal pump P is automatically initiated by the two cooperating ejectors S_I and S_{II} during the starting of the pump by the motor M. On the pipe knee K of the suction conduit the vent valve V is

arranged, the magnet coils of which are included in the circuit of the motor M by way of the conductor 29.

As soon as for starting the pump the motor is connected, the body of the valve V is pressed on its seat by action of the electromagnets, thereby sealing the suction conduit in the required air-tight manner. When the motor is disconnected the valve body is released, thus permitting of air flowing into the suction conduit as indicated by the arrows in Fig. 3, whereupon the water circulation in the suction pipe is immediately interrupted and a siphon effect in the pump prevented, so that the installation remains at all times filled up to the level n .

The effect of the vent valve is instantaneous and sure to take place, so much more, as the valve is at no time in contact with the liquid conveyed through the pump, and with the vent valve body in any position a suction effect is present in the suction conduit. Consequently, the vent valve is ensured against rusting by corrosive action of all impurities contained in the liquid, and its parts are prevented from binding one on the other.

I claim:

1. In a pumping installation including an air-eliminating device, in combination, a centrifugal pump, an ejector inserted between the pressure conduit and the suction conduit of said pump and acting in the direction of the suction action of the latter, a suction chamber provided on said ejector, a pipe knee inserted in the suction conduit of said pump to extend from said suction chamber above the latter, an air-separator included in the pressure conduit of said pump, a second ejector inserted between the pressure conduit of said pump and said air-separator and acting in the direction of the pump delivery, and a suction chamber provided on said second ejector and communicating with said first ejector.

2. In a pumping installation actuated by an electric motor and including an air-eliminating device, in combination, a centrifugal pump, an ejector inserted between the pressure conduit and the suction conduit of said pump and acting in the direction of the suction action of the latter, a suction chamber provided on said ejector, a pipe knee inserted in the suction conduit of said pump to extend from said suction chamber above the latter, an air-separator included in the pressure conduit of said pump, a vent valve controlled by said motor and communicating with said suction conduit for admitting atmospheric air thereto, at least one electromagnet associated with said vent valve, an operative connection interposed between said electromagnet and said vent valve, electrical connecting means arranged between said magnets and said motor for closing said valve,

due to current flowing through said motor, a second ejector inserted between the pressure conduit of said pump and said air-separator and acting in the direction of the pump 5 delivery, and a suction chamber provided on said second ejector and communicating with said first ejector.

3. In a pumping installation actuated by an electrical motor and including an air-10 eliminating device, in combination, a centrifugal pump, an ejector inserted between the pressure conduit and the suction conduit of said pump and acting in the direction of the suction action of the latter, a suction chamber 15 provided on said ejector, a pipe knee inserted in the suction conduit of said pump to extend from said suction chamber above the latter, an air-separator included in the pressure conduit of said pump, a vent valve controlled by said motor and communicating 20 with said suction conduit for admitting atmospheric air thereto, a valve casing for said vent valve, a valve body vertically slidably arranged in said valve casing, air inlet openings 25 provided in said valve casing above the valve seat, two electromagnets associated with said vent valve, an operative connection interposed between said electromagnets and said vent valve, electrical connecting means 30 arranged between said magnets and said motor for closing said valve due to current flowing through said motor, a second ejector inserted between the pressure conduit of said pump and said air-separator and acting in 35 the direction of the pump delivery, and a suction chamber provided on said second ejector and communicating with said first ejector.

4. In a pumping installation actuated by an electrical motor and including an air-40 eliminating device, in combination, a centrifugal pump, an ejector inserted between the pressure conduit and the suction conduit of said pump and acting in the direction of 45 the suction action of the latter, a suction chamber provided on said ejector, a pipe knee inserted in the suction conduit of said pump to extend from said suction chamber above the latter, an air-separator included in the 50 pressure conduit of said pump, a vent valve controlled by said motor and communicating with said suction conduit for admitting atmospheric air thereto, a valve casing for 55 said vent valve, a valve body vertically slidably arranged in said valve casing, air inlet openings provided in said valve casing above the valve seat, two electromagnets associated with said vent valve, an armature arranged in each electromagnet, a common 60 housing provided for said vent valve and said electromagnets, two intercrossing links centrally attached to said valve body and pivotally connected at their one ends with said housing and at their other ends with 65 said armatures of said electromagnets re-

spectively, electrical connecting means arranged between said magnets and said motor for closing said valve due to current flowing through said motor, a second ejector inserted between the pressure conduit of said pump 70 and said air-separator and acting in the direction of the pump delivery, and a suction chamber provided on said second ejector and communicating with said first ejector.

In testimony whereof I have signed my 75 name to this specification.

HERMANN LAUCHENAUER.
